PAUL F. COX AND JOSEPH L. COX, OF CHICAGO, ILLINOIS, ASSIGNEES TO THE GOSS PRINTING PRESS COMPANY, OF CHICAGO, ILLINOIS, A CORPORATION OF ILLINOIS

THROW-OFF MECHANISM FOR TRAVELING-CYLINDER PRESSES

Application filed November 19, 1928. Serial No. 320,320.

Our invention relates to printing presses for throwing traveling impression cylinders on and off impression in which the web is printed by the co-operation of a stationary type bed and traveling impression cylinder such for example as shown in Cox Patents No. 988,548 of April 4, 1911, and No. 1,457,501, of June 5, 1923, which presses are provided with mechanism for throwing the impression cylinders off impression after their impression stroke, and keeping same clear of the type form on the stationary beds during their return stroke (during which time the web of paper is advanced between the type and cylinders) and for then throwing the cylinders on impression so that they will press the web into contact with the type forms to take an impression upon the web of paper during their impression stroke.

More particularly the invention is an improvement upon the means for raising and lowering, and holding, the reciprocating cylinders in "on impression" and "off impression" positions shown, described and more broadly claimed in our Letters Patent No. 1,747,662, dated Feb. 18, 1930, and the present invention includes novel closed or race cams operated by the swinging movement of the pitman, so formed that the swinging movement of the pitman relative to the crossheads will positively and accurately cause both the "throwing on" and "throwing off" of the impression cylinders and also hold them in the desired positions on their respective strokes.

While the invention is primarily designed for use in a web perfecting press, it is applicable to single acting presses; and to sheet presses; and to other types of machines in which traveling cylinders are employed which are to be "thrown off impression" on one stroke and "thrown on impression" on the return stroke.

We will explain the invention with reference to the accompanying drawings which illustrate the invention as applied to a well known type of traveling cylinder web perfecting press, sufficient of such press being illustrated to enable the invention to be clearly understood by those familiar with

the art. The claims summarize the novel features of construction and novel combinations of parts for which protection is desired.

In the drawings:

Fig. 1 is a partial side elevation of a web printing press showing our novel mechanism for throwing the cylinders "on" or "off" impression and for holding the same "on" or "off" impression while the cylinders are passing over the forms. 55

Fig. 2 is an enlarged detailed view showing by means of dotted lines some of the different positions assumed by the cams and cylinders during the operation of the press. 60

Fig. 3 is a detail plan view of the parts shown in Fig. 2. 65

Fig. 4 is a view similar to Fig. 2 showing a slight modification of the invention.

Fig. 5 is a view similar to Fig. 4, showing a slight modification. 70

In the drawings 1 and 1^a designate parallel type beds arranged one over the other in a suitable main frame 9.

A traveling impression cylinder 2 cooperates with bed 1^a and a traveling impression cylinder 2^a co-operates with bed 1^a, said cylinders are mounted in bearings in crossheads 3 which are guided in longitudinal guideways 9^a in the sides of the press frame. Said crossheads 3 are reciprocated so as to move the cylinders 2 and 2^a back and forth over the beds, by means of pitmen 4 connected to pins or studs 3^a on the crossheads 3, and to crank pins 4^b on crank gears 4^a, mounted on a shaft 4^c on the main frame. 75

The cylinders are usually mounted in adjustable bearings which can be raised or lowered to throw the cylinders on or off impression; ordinarily eccentric rocking bushings are used, and such bushings are indicated at 5 in the drawings on the crosshead. 85

In such presses a web *w* is led over suitable guide rollers from the web roll to and successively between the lower cylinder 2^a and bed 1^a, and then between the upper cylinder 2 and the bed 1, to the delivery; and suitable means is provided for intermittently drawing the web forward between successive impressions, while the cylinders are "thrown off impression" but traveling over the beds, 95 100

The means for feeding, guiding, leading and shifting the webs may be of any desired construction and are well understood, and form no part of the present invention. The general construction and arrangement of the aforesaid parts in this type of presses are well known and need no further detailed explanation herein.

In the press shown the cylinders are "on impression" and print only when moving on one stroke say to the left, and are thrown "off impression" during their return stroke.

In the construction each eccentric bushing 5 is provided with an arm 5^b which preferably carries a stud or roller 5^c which engages a closed or race cam slot in a cam member 6 formed on or rigidly attached to the pitmen 4.

The operation of each cam 6 upon the related eccentric bushing 5 is the same, for each and both cylinders 2 and 2^a, and the description of the construction and operation of one will explain both.

Each cam 6 is mounted on and fixed relatively to the pitmen 4 when in operation, but has a rocking movement relative to the related cylinder bushing during the reciprocation of the cylinders, due to the swinging movement of the end of the pitman (on which the cam is mounted) upon the pin 3^a of the crosshead.

As shown in Figs. 2 and 4 each cam member 6 has a cam slot provided with an approximately central cam portion 6^a and with dwell portions 6^b and 6^c at opposite ends of cam portion 6^a.

Each cam 6 being formed on or rigidly attached to the pitman 4 is rocked by the swinging movement of this pitman on the pin 3^a; the swinging movement of the pitmen 4 being due to the orbital movement of the pin 4^b by the wheel 4^a. The upper and lower cams 6, Figs. 1 and 2, are alike but are reverse one to the other.

When the cam portion 6^a moves pin 5^c upwardly it will rock the eccentric bushing 5 so as to move the cylinder away from the line of impression thus throwing the cylinder "off impression". When the cam portion 6^a moves pin 5^c downwardly upon the cam 6^c it will rock the eccentric bushing 5 so as to move the cylinder 2 toward the line of impression, thus throwing the cylinder "on impression".

As shown in Fig. 2 the wheel 4^a rotates anti-clockwise and consequently the cam members 6 will be rocked in a clockwise direction during the time that the pin 4^b is moving 180° from a position vertically above the axis 4^c of the wheel 4^a to a position vertically below it; and (during the next one-half revolution of the wheel 4^a) the cams 6 will be rocked anti-clockwise during the movement of the pin 4^b 180° from a position directly below the axis of wheel 4^a to

a position directly above said axis. Of course the extent and time of movement of the cam 6 varies according to the angularity of the pin 4^b relative to the axis of the wheel 4^a. When the pin 4^b is on the dead center (between the pin 3^a and the axis of wheel 4^a) the cam 6 is practically still, but it begins to reverse its movement as the pin 4^b passes the dead center.

Assuming that it is preferable that the cylinder be "off impression" during the outward stroke of the crossheads (i. e. away from the wheel 4^a) and should be "on impression" during the inward stroke of the crossheads (i. e. towards the wheel 4^a) the portions 6^a, 6^b, 6^c of the cam slots are so formed and calculated—(with respect to the swinging movement of the pitmen 4 on the pin 3^a, and consequent rocking movement of the cam 6 relative to said pin,)—that on the inward stroke of the cylinder, and after it has cleared the type-form on the bed, the cam portions 6^a will begin to move the pins 5^c upward and rock the eccentrics 5 so as to raise the cylinders off impression; and the pins 5^c will enter and move in the dwells 6^b of the slots and hold the cylinders off impression during the outward return stroke of the cylinders until they have cleared the outer end of the type forms on the bed; then cam portions 6^a will again reversely engage the pins 5^c and move them downwardly and rock the eccentric 5 so as to lower the cylinders to the line of impression before the cylinders reach the printing form, during their inward stroke; thus throwing the cylinders on impression; and the pins 5^c will enter dwells 6^c and hold the cylinders on impression until they have cleared the inner ends of the type forms on their inward stroke; then the cam portions 6^a will again engage the pins 5^c and again move the cylinders off impression as above described. Thus after the cylinders clear the forms on their inward printing stroke they are thrown "off impression" and are held off impression during their outward return stroke until they have cleared the outer end of the forms; then the cylinders are thrown "on impression" and held in such position during their inward printing stroke until they have again cleared the inner ends of the forms and then they are again "thrown off" impression as described.

By reason of the rocking of the cam 6 the cam portion 6^a is caused to move the pin 5 upwardly adjacent one end of the stroke of the cylinders, and downwardly adjacent the other end of the stroke of the cylinders and the dwell portions 6^b and 6^c of the cam slot will alternately hold the cylinders in thrown on and thrown off positions as described, and the cylinders are held in such thrown on or thrown off positions without requiring any auxiliary devices such as shown in Cox Patent 1,457,501, and no other auxiliary means

for locking the cylinders in on or off position is required, and the doing away with these auxiliary locking devices obviously simplifies construction and lessens cost of manufacture. It will further be seen that in the present invention we have simplified the construction shown in our aforesaid Letters Patent No. 1,747,662 and that in the present case by means of a closed cam slot, we are able to dispense with one arm and one pin on the eccentric bushing and to simplify the construction of the cam member itself.

The pin 3^a could be placed in direct line with the center of the axes of the impression cylinders 2, 2^a, but in order to accentuate the movement of the cams 6 relative to the axes of the cylinders or bushings 5, the pin 3^a may be placed to one side of a plane including the centers of both line impression cylinders; preferably we place it to the outer side of such plane. By thus locating the pin 3^a the amount of rocking movement of the cams 6 relative to the axes of the cylinders is amplified over what their movement would be if the pin 3^a was in line with the axes of the cylinders; and this additional augmented movement is taken advantage of in calculating the time and throw of the cam portions 6^a of the cam slots and the dwell portions 6^b and 6^c thereof.

The arm 5^b carrying the pin 5^c can be formed integral with the eccentric 5 if desired, or can be formed on a plate 5^a which can be adjustably secured to one end of the bushing by means of slots and bolts 5^t as indicated in Fig. 4, which will enable the eccentrics 5 to be independently adjusted rotatorily of the bearings, while maintaining the proper relative positions and engagement of the pins 5^c and the cam slots in cam members 6.

When the press has two beds and two cylinders as indicated in Figs. 1 and 2, each cylinder may be operated in the manner described; but the cam slot in the lower cam member is reverse to that in the upper cam member, to produce the proper similar simultaneous raising and lowering of the cylinders in the manner above described.

In the modification shown in Fig. 5 the cam members 6^x are shown as formed separately from the pitmen 4 and secured thereto by means of bolts 6^b. Each cam member 6^x is provided with a slot having cam portion 6^a and dwells 6^b and 6^c at opposite ends of this cam portion, as in Figs. 1 and 2, and each cam slot operates the adjacent eccentric as and for the purpose hereinbefore described. The slot in the lower cam member 6^x in this instance is shown as lying to the outside of pin 5^a and the slot in the upper cam member as lying to the inside of pin 5^a. The rollers 5^c could be adjustably mounted on the eccentrics

5, as by means of adjusting bolts 5^k as indicated in Fig. 5.

If desired a single cam member and pin for operating one cylinder can be utilized to effect the "throwing on" or "throwing off" of both cylinders: One means of so doing is illustrated in Fig. 4, in which figure the arm 5^b of the upper bushing is provided with an extension 5^d connected by a rod 5^w with an arm 5^x on the eccentric bushing 5 in which the lower cylinder 2^a is journaled. The rod 5^w may be provided with an adjusting member 5^y to regulate or adjust the length of said rod or distance between the pivotal connections of the rod 5^w to the arms 5^d and 5^x respectively. With this construction it is obvious that when the upper cam member 6 rocks the eccentric bushing 5 of the upper cylinder, as hereinabove explained, the rocking movement of such upper bushings 5 will through the connections (5^d—5^w—5^x) similarly move the eccentric bushings of the lower cylinder 2^a; and consequently both cylinders 2 and 2^a will be thrown on or thrown off impression, and be held on or off impression, as above described, by the use of only a single set of cams 6 and pins 5^c.

While rocking eccentric bushings 5 provide a simple and easy means of raising and lowering the cylinders, other devices for raising and lowering them might be employed within the scope of our invention.

We claim:

1. In a printing press having a traveling cylinder, reciprocating crossheads for moving the cylinder, and means on a crosshead for throwing the cylinder on and off impression; pitmen pivotally connected with the crossheads at points to one side of the plane containing the axes of the cylinders; and means on the pitmen whereby the said throwing on and off means are operated as the crossheads are reciprocated.

2. In a printing press having a stationary bed, a traveling impression cylinder cooperating with the bed; crossheads in which said cylinder is mounted; and means on the crossheads for throwing the cylinder on and off impression; crank wheels, pitmen pivotally connected with the crank wheels and with the crossheads at points to one side of the plane containing the axes of the cylinders; and cams on the pitmen adapted to actuate the said throwing on and off means as the crossheads are reciprocated.

3. In a printing press having traveling cylinders, reciprocating crossheads for moving the cylinders, and means on the crossheads for throwing the cylinders on and off impression, pitmen pivotally connected with the crossheads at points to one side of a plane containing the axes of both cylinders; and members fixedly mounted on the pitmen and directly engaging the said throwing on and

off means whereby the latter are operated as the crossheads are reciprocated.

4. In a printing press having stationary beds, traveling impression cylinders cooperating with the beds; crossheads in which said cylinders are mounted; means on the crossheads for throwing the cylinders on and off impression; crank wheels, pitmen pivotally connected with the crank wheels at points to one side of a plane containing the axes of both cylinders; and cams on one of the pitmen adapted to actuate the said throwing on and off means as the crossheads are reciprocated.

5. In a printing press having stationary beds, traveling cylinders cooperating with the beds; crossheads for moving said cylinders; means on the crossheads for throwing the cylinder on and off impression; reciprocable pitmen pivotally connected with the crossheads at points to one side of a plane containing the axes of both cylinders; and means fixedly mounted on the pitmen whereby the said throwing on and off means is operated.

6. In a printing press having stationary beds, traveling cylinders cooperating with the beds; crossheads for moving said cylinders; means on the crossheads for throwing the cylinder on and off impression; reciprocable pitmen pivotally connected with the crossheads at points to one side of a plane including the centers of both cylinders; and closed cams on one of the pitmen whereby the said throwing on and off means is operated by the pitman while the crossheads are moving and the cylinders held off impression on one stroke and on impression on the return stroke.

7. In a printing press having a traveling cylinder mounted in reciprocating crossheads; oscillating devices on the crossheads for throwing the cylinder on and off impression; and pitmen pivotally connected with the crossheads and closed cams carried by the pitmen whereby the said throwing on and off devices are positively operated in both directions by the swinging movement of the pitman.

8. In a printing press having a traveling cylinder mounted in reciprocating crossheads; oscillating devices on the crossheads for throwing the cylinder on and off impression; and pitmen pivotally connected with the crossheads at points to one side of the center of the cylinder; and closed cams on one of the pitmen whereby the said throwing on and off devices are positively operated in both directions by the swinging movement of the pitman.

9. In a printing press having a stationary bed, a traveling cylinder; crossheads in which said cylinder is mounted, means on the crossheads for throwing the cylinder on and off impression, crank wheels, and pitmen pivotally connected with the crank wheels and also pivotally connected with the crossheads; members on the pitmen having cam slots en-

gaging members on the throw off means to operate said throwing on and off means as the crossheads are reciprocated.

10. In a printing press having a stationary bed, a traveling cylinder; crossheads in which said cylinder is mounted, means on the crossheads for throwing the cylinder on and off impression, crank wheels, and pitmen pivotally connected with the crank wheels and also pivotally connected with the crossheads at points to one side of the center of the cylinder; cams on the pitmen having slots engaging members on the throw off and on means whereby said means are operated as the crossheads are reciprocated to hold the cylinder off impression on one stroke and on impression on the return stroke.

11. In a printing press having a stationary bed and traveling cylinder cooperating with said bed; crossheads in which the cylinder is mounted; devices on the crosshead for throwing the cylinder on and off impression; and pitman pivotally connected with the crosshead; a member on the end of the pitman adjacent the pivotal connection thereof to the crossheads provided with a cam slot engaged by a member of the said devices, said cam slot causing the said devices to operate while the crosshead is moving and move and hold the cylinder off impression on one stroke and on impression on the return stroke.

12. In a printing press having a stationary bed and traveling cylinder cooperating with said bed, a crosshead in which said cylinder is mounted; a crank wheel, a pitman pivotally connected with the crank wheel and pivoted to the crosshead; means on the crosshead for throwing the cylinder on and off impression, including an arm extending adjacent the pivoted end of the pitman; a cam member on the pitman adjacent the pivotal connection thereof to the crosshead having a cam slot engaged with said arm whereby the said throwing on and off means is actuated as the crossheads are reciprocated to hold the cylinder off impression on one stroke and on impression on the return stroke.

13. In a printing press having stationary beds and traveling cylinders cooperating with said bed; crossheads in which the cylinders are mounted; devices on the crossheads for throwing the cylinders on and off impression; and pitmen pivotally connected with the crossheads at a point to one side of a plane including the centers of the cylinders; cam members on the pitmen adjacent the pivotal connection thereof to the crossheads having cam slots engaging members of the said devices, said slots causing the said devices to operate while the crossheads are moving and move and hold the cylinders off impression on one stroke and on impression on the return stroke.

14. In a printing press having stationary beds and traveling cylinders cooperating with

said beds, crossheads in which said cylinders are mounted; pitmen pivotally connected with the crossheads at points to one side of a plane including the centers of the cylinders,
5 means on the crossheads for throwing the cylinders on and off impression including an arm extending adjacent the pivoted end of the pitmen; cam members on the pitmen adjacent the pivotal connections thereof to
10 the crossheads, said cam members having cam slots engaged with said arm, whereby the said throwing on and off means are actuated as the crossheads are reciprocated to hold the cylinders off impression on one stroke and
15 on impression on the return stroke.
